HEATER

Lev A. Mekler, Chicago, Ill., assignor to Universal
Oil Products Company, Chicago, Ill., a corpora-
tion of Delaware

Application June 26, 1939, Serial No. 281,073

6 Claims. (Cl. 122—356)

The invention particularly refers to an improved form of heater of the type now generally known in the oil refining industry as an "equiflux" heater, the particular form of heater herein provided having three individual cells or compartments each independently fired along opposite side walls of the cell and each provided with a plurality of tubular elements interconnected in such a manner as to simultaneously heat two 10 separate streams of fluid under substantially identical conditions with definite control of the rate of heating and the temperature curve obtained in different sections of each stream.

This improved form of heater is particularly 15 advantageous as applied to that type of hydrocarbon oil conversion known as "reforming," where relatively light hydrocarbon oil distillates such as gasoline or gasoline fractions of inferior antiknock value, naphtha and the like are converted into high yields of good antiknock gasoline. In such service the heater is adaptable to high charging stock capacities, the flow of oil through the various tubular elements and the various cells being such that the total charging 25 stock may be divided into two streams of substantially equal quantity to avoid excessive pressure drop through the heating coil, while each separate stream is simultaneously heated under substantially identical conditions and the heating 30 curve most advantageous for this type of conversion is obtained in both streams.

The advantageous features of the invention will be clearly understood by those familiar with the art with reference to the accompanying drawings. Figure 1 of the drawings is a cross-sectional elevation of one specific form of heater provided by the invention and illustrates one specific flow which may be employed for simultaneously heating two substantially equal streams 35 of the same oil under substantially identical conditions. Figures 2, 3, and 4 each illustrate a different modification of the flow illustrated in Figure 1, the general contour of the heater being shown by broken lines in Figures 2, 3 and 4.

45 Referring to Figure 1, the three individual cells or compartments of the heater are designated as 1, 2 and 3, cells 1 and 3 being disposed on opposite sides of the central cell 2. The two outer cells are each provided with a side wall 4 and walls 5 and 6 separate cell 2 from cells 1 and 3, respectively. Walls 5 and 6 may be of the section- 50 alized double suspended insulated and air-cooled construction shown in the drawings or of any other desired conventional construction, not illus- 55 trated. For example, partition walls of solid

masonry comprising fire-brick or other refractory shapes laid up in a conventional manner may be employed. The same applies to the outer side walls 4 and end walls (not shown) and other details of the construction illustrated may be 5 modified in any conventional manner, since the invention is concerned with the general arrangement and disposition of the fluid conduits rather than structural details. Each cell is provided with a roof 7 and end walls which are now shown 10 in this particular view of the heater.

The lower portion 8 of cell 1, which is of reduced cross-sectional area as compared with the upper portion of the cell, is a fluid heating zone containing a plurality of horizontal rows of horizontally disposed tubes 9, which comprise tube bank 10 of the heater. The upper portion of cell 1 is a radiant heating zone containing two vertical rows of horizontally disposed tubes 11, which comprise tube bank 12 of the heater, this 20 bank being located centrally between walls 4 and 5 of cell 1 and adjacent tubes in the two rows being arranged in staggered formation.

The lower portion 13 of cell 3 is substantially the same as the lower portion 8 of cell 1 and is a 25 fluid heating zone containing tube bank 15 substantially identical with bank 10 of cell 1 and comprising a plurality of horizontal rows of horizontally disposed tubes 14. The upper portion of cell 3, which corresponds to the upper portion 30 of cell 1, is a radiant heating zone containing a tube bank 17 which, like bank 12 of cell 1, is disposed centrally between the side walls of the cell and comprises two vertical rows of horizontally disposed tubes 16, the adjacent tubes in the two 35 rows being arranged in staggered formation.

Cell 2 also has a lower portion 18 similar to the lower portions 8 and 13 of cells 1 and 3, respectively, and zone 18 is a fluid heating zone containing a plurality of horizontal rows of horizontally disposed tubes 19 comprising tube bank 20. Bank 20 is divided into a right-hand and a left-hand section each containing an equal number of tubes. Provision may be made for passing a single stream of fluid in series through 45 the tubes of each section of bank 20, as illustrated, or, when desired, the sections of this bank may be further divided by well known means, not illustrated, to permit the passage of any desired number of parallel streams therethrough.

50 The upper portion of cell 2 is a radiant heating zone containing four vertical rows of horizontally disposed tubes 21 located centrally between the side walls 5 and 6 of this cell and comprising tube bank 22. Bank 22 is divided into a right-hand 55

and a left-hand section each containing an equal number of tubes, the adjacent tubes in adjacent rows of bank 22 being arranged in staggered formation.

5 In the particular case here illustrated, each of the cells 1, 2 and 3 is fired in a downward direction through firing ports 23 provided in the roof 1 adjacent side walls 4, 5 and 6 by means of burners 24. Each of the burners points at an 10 angle toward the adjacent side wall so that the flames and hot combustion gases resulting from the combustion of fuel in the various cells impinge against said adjacent walls and pass downwardly thereover, heating the same to a highly 15 radiant condition. The fuel is supplied through the burners and the air for combustion is supplied, in part, through the burners and, in part, directly through firing ports 23 by the inductor action of the mixture issuing from the burners 20 or, when desired, a forced-draft fan or blower, not illustrated, may be employed for supplying air at atmospheric temperature, air preheated by contact with the walls of the furnace setting 25 or air preheated by heat exchange with flue gases through and around the burners. Preferably, the burners and firing ports are arranged in a row adjacent each of the walls 4 and each side of the walls 5 and 6 within the cells so that there is a substantially continuous sheet of flames and 30 hot combustion gases travelling downward over the fired surface of each of these walls, although this arrangement is not illustrated in the particular view of the heater herein shown.

Heat is imparted to opposite sides of each of 35 the tube banks 12 and 17 by direct radiation, a major portion of the heat transmitted to the oil flowing through the tubes of banks 12 and 17 being imparted to the tubes by radiation from the flames, hot combustion gases and highly heated 40 walls of the cells wherein they are disposed at relatively high rates of heat transfer.

The combustion gases, from which a major portion of their radiant heat has been extracted by transmission to banks 12 and 17, pass downwardly through the zones 8 and 13 of the respective cells 1 and 3 in direct and intimate contact with the tubes of banks 10 and 15, respectively, whereby a substantial quantity of fluid heat is extracted from the gases, and they then pass 45 through the respective flues 25 and 26 to a suitable stack, not shown, a single stack being preferably employed for all three of the cells.

Predominantly radiant heat is also imparted to each of the tubular elements of bank 22 from the 55 flames, hot combustion gases and highly heated side walls of cell 2. However, with the particular arrangement here illustrated, the tubes of the two central rows of bank 22 are each partially shielded on one side by the adjacent tubes of the 60 two outer rows, and vice versa, so that, even if identical firing conditions were employed in all three cells, the tubes of bank 22 would not receive heat at such a high rate as those of banks 12 and 17.

65 The combustion gases from the upper portion of cell 2, from which a substantial portion of their radiant heat has been extracted, pass downwardly through zone 18 in direct and intimate contact with the tubular elements of bank 70 20, which receive a large amount of fluid heat from these gases, and the gases are thence directed through flue 27 to the stack.

The uppermost rows of each of the banks 10, 75 15 and 20 will also receive a substantial amount

of radiant heat, primarily from the hot combustion gases and from the highly heated walls.

It is also within the scope of the invention to fire any or all of the cells of the heater in an upward rather than a downward direction, in which case the flames and hot combustion gases will travel upwardly from burners disposed adjacent the floor over the side walls to the fluid heating zone, which is disposed above rather than beneath the radiant heating zone to a flue disposed above the fluid heating zone.

The adjacent tubes of each of the banks are connected in series at their ends by means of suitable return bends which are located outside the heated zone and do not appear in this particular view of the heater. The single lines connecting the adjacent tubes and connecting the various tube banks indicate the flow therethrough in each of the figures of the drawings, the general direction of flow being indicated by arrows.

The flow illustrated in Figure 1 is as follows: The oil to be treated enters the heater as two separate streams 28 and 28' of substantially equal volume. The left-hand stream flows in a general upward direction through the left-hand section 25 of tube bank 20 and is transferred from the uppermost tube of this bank through line 29 to the lower portion of bank 10, through which it flows in a general upward direction and is thence transferred through line 30 to the lower end of tube bank 12 and flows in series through adjacent tubes in the opposite rows of this bank in a general upward direction. This stream is transferred from the upper end of tube bank 12 30 through line 31 to the upper end of the left-hand section of tube bank 22 and flows downwardly in series through the adjacent tubes in the two rows of this section to its lower end. The right-hand stream 28' follows a substantially identical course through the right-hand section 35 of bank 20, through line 32, bank 15, line 33, bank 17, line 34 and the right-hand section of bank 22, in the order given, and the two separately heated streams emerge from the lower ends of the right and left-hand sections of bank 22 40 to commingle in line 35 through which they are directed to subsequent portions of the system not pertinent to the present invention.

With the particular arrangement and flow illustrated and above described, when reforming 50 gasoline or other light hydrocarbon oil distillate, substantially identical firing conditions are preferably employed in each of the cells 1 and 3 and on opposite sides of each of the cells, while somewhat milder firing conditions are employed in 55 cell 2, with substantially equal firing on opposite sides of this cell. Thus, the two streams of oil are substantially equally heated and each stream attains a high cracking temperature within the respective banks 12 and 17 and is maintained for 60 a predetermined time in bank 22 at a substantially uniform temperature close to that prevailing at the outlet of banks 12 and 17. By thus employing banks 20, 15, 10, 12 and 17 as heating and cracking sections and employing bank 22 as a 65 soaking section, a heating curve will be obtained (by plotting the time in the coil against the temperature rise) which rises rather steeply to or near the maximum temperature attained and has a relatively flat end, representing the soaking 70 section, this being the ideal heating curve for reforming.

In Figure 2, the tubes of each of the banks 10, 15 and both sections of bank 20 are connected as illustrated in Figure 1, the left-hand section 75

of bank 20 being connected with bank 10 and the right-hand section of bank 20 being connected with bank 15, but instead of connecting adjacent tubes in opposite rows of banks 12, 17 and the right or left-hand sections of bank 22 in series, adjacent tubes in the same row are connected in series and parallel flow is employed in the two rows of each bank.

In Figure 3, the arrangement of banks 10, 15, 20, 12 and 17 and the flow therethrough is the same as illustrated and described in conjunction with Figure 2, while the flow through the right and left-hand sections of bank 22 is as illustrated in Figure 1, except that the general direction of flow through the two rows of each section of bank 22 is reversed. The left-hand section of bank 20 and banks 10, 12 and the left-hand section of bank 22 are connected in series in the order named, while the right-hand section of bank 20 and banks 15, 17 and the right-hand section of bank 22 are connected in series in the order named.

In Figure 4, the arrangement and flow through banks 10, 15 and 20 is the same as illustrated in Figure 1, the arrangement and flow through banks 12 and 17 also being the same as illustrated in Figure 1 and the arrangement and flow through the right-hand and left-hand sections of bank 22 being the same as illustrated in Figure 1.

The flow illustrated in Figures 2, 3 and 4 each give still greater flexibility with respect to control of the heating curve than that illustrated in Figure 1, since firing conditions on opposite sides of each tube bank may be independently controlled and by varying the amount of excess air employed, variations between the rates of heating obtained in the upper and lower portions of each cell may be accomplished. The flow illustrated in Figure 2 provides the greatest degree of flexibility, while that illustrated in Figure 3 provides greater flexibility with respect to banks 12 and 17 as compared with that illustrated in Figure 1, and the flow illustrated in Figure 4 provides greater flexibility with respect to bank 22 as compared with that illustrated in Figure 1.

Many modifications of the specific form of heater illustrated are possible within the scope of the invention and will be apparent to those familiar with the art. For example, although each of the figures of the drawings illustrates a separate fluid heating bank communicating with each radiant heating compartment, the invention specifically contemplates a multiple compartment heater having an odd number of radiant heating zones and a single fluid heating zone communicating with each of the radiant heating zones. In such cases, the tube banks 10, 15 and 20 may be replaced by a single tube bank divided into a plurality of substantially identical sections equal in number to the number of separate streams supplied to the heater, each stream being passed through one of said separate sections.

I claim as my invention:

1. A heater for fluids comprising, in combination, an odd number of separately fired heating compartments, a plurality of tubular elements in each compartment disposed to receive heat by direct radiation from flames and hot combustion gases resulting from burning of fuel in said compartments and by radiation from hot refractory walls of the compartments, means for relatively mild firing of one of said compartments and means for more severe substantially uniform fir-

ing of the other compartments, means for passing a separate stream of the fluid to be heated through the tubular elements in each of said other compartments and means for thence passing each of said separate streams through separate sections of the tube bank comprising said tubular elements in the mildly heated compartment, the arrangement of said separate sections and of the tubular elements in each compartment and the form of the compartments and arrangement of the means for firing the same being such that each of said separate streams is substantially uniformly heated.

2. The heater defined in claim 1, wherein each of said compartments has substantially vertical side walls and the means for firing each compartment comprises separate sets of burners arranged to direct a separate sheet of flames and hot combustion gases over each of said side walls in a substantially vertical direction, the tubular elements of each compartment comprising a bank having a plurality of substantially parallel vertical rows of horizontally disposed tubes, each of said banks being located centrally between said side walls of the compartment in which it is disposed, the adjacent tubes in each row of the individual banks in each of said other compartments being connected for the series of flow of fluid therethrough and the adjacent rows of tubes in each of the last named banks being connected for the series flow of fluid therethrough.

3. The heater defined in claim 1, wherein each of said compartments has substantially vertical side walls and the means for firing each compartment comprises separate sets of burners arranged to direct a separate sheet of flames and hot combustion gases over each of said side walls in a substantially vertical direction, the tubular elements of each compartment comprising a bank having a plurality of substantially parallel vertical rows of horizontally disposed tubes, each of said banks being located centrally between said side walls of the compartment in which it is disposed, the adjacent tubes in each row of the individual banks in each of said other compartments being connected for the series flow of fluid therethrough and the adjacent rows of tubes in each of the last mentioned banks being connected for the series flow of fluid therethrough in countercurrent directions.

4. The heater defined in claim 1, wherein each of said compartments has substantially vertical side walls and the means for firing each compartment comprises separate sets of burners arranged to direct a separate sheet of flames and hot combustion gases over each of said side walls in a substantially vertical direction, the tubular elements of each compartment comprising a bank having a plurality of substantially parallel vertical rows of horizontally disposed tubes, each of said banks being located centrally between said side walls of the compartment in which it is disposed, the adjacent tubes in different rows of each bank in said other compartments being connected for the series flow of fluid therethrough.

5. The heater defined in claim 1, wherein each compartment has substantially vertical side walls, the means for firing each compartment comprising separate sets of burners arranged for directing a separate sheet of flames and hot combustion gases over each of said side walls in a substantially vertical direction, the tubular elements in each of said other compartments comprising a single bank having a plurality of ver-

- tical rows of horizontally disposed tubes connected for the series flow of fluid through the several tubes of each bank and said separate sections of the tube bank in said one compartment each comprising a plurality of vertical rows of horizontally disposed tubes, the adjacent tubes in each row of said separate sections being connected for the series flow of fluid therethrough and the adjacent vertical rows in each of said 10 separate sections being connected for the series flow of fluid therethrough, the tube bank in each of said compartments being located centrally between said side walls of the compartment in which they are disposed.
- 15 6. The heater defined in claim 1, wherein each compartment has substantially vertical side walls, the means for firing each compartment comprising-

ing separate sets of burners arranged for directing a separate sheet of flames and hot combustion gases over each of said side walls in a substantially vertical direction, the tubular elements in each of said other compartments comprising a single bank having a plurality of vertical rows of horizontally disposed tubes connected for the series flow of fluid through the several tubes of each bank and said separate sections of the tube bank in said one compartment each comprising a plurality of vertical rows of horizontally disposed tubes, the adjacent tubes in different rows of said separate sections being connected for the series flow of fluid therethrough and each of said banks being located centrally between said 15 walls of the compartment wherein it is disposed.

LEV A. MEKLER.
